US0D1082784S

(12) **United States Design Patent** (10) **Patent No.:** **US D1,082,784 S**
(45) **Date of Patent:** **** Jul. 8, 2025**

(54) **NETWORK DEVICE**

(71) Applicant: **Cisco Technology, Inc.**, San Jose, CA (US)

(72) Inventors: **Nicholas James Kawamoto**, Novato, CA (US); **Parmis Taidy**, Tampa, FL (US); **Brad Andrew Palladino**, Oakland, CA (US); **Hyunsoo Lee**, San Ramon, CA (US); **Daniel Neal Johnson**, Louisville, OH (US); **Kexian Huang**, Shanghai (CN); **Timothy Allen Frank**, Medina, OH (US); **Ehsan Ettehadieh**, Oakland, CA (US); **Jessica Marie Judson**, San Francisco, CA (US)

(73) Assignee: **Cisco Technology, Inc.**, San Jose, CA (US)

(**) Term: **15 Years**

(21) Appl. No.: **29/916,683**

(22) Filed: **Nov. 14, 2023**

(51) LOC (15) Cl. **14-02**

(52) U.S. Cl. **USPC D14/356**

(57) **CLAIM**

The ornamental design for a network device, as shown and described.

DESCRIPTION

FIG. 1 is a top, front, right-side perspective view of a network device;

FIG. 2 is a bottom, back, right-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the network device that form no part of the claimed design.

1 Claim, 8 Drawing Sheets
